FIG. 1

FIG. 2

FIG. 3

FIG. 1 is a left top perspective view of a chess board embodying my new design, characterized by a multiplicity of islands of different sizes in the field of defense and a plurality of islands of uniform size in the field of play.

FIG. 2 is a bottom rear perspective view.

FIG. 3 is a plan view, similar to that shown in FIG. 1, but drawn to a larger scale.

I claim:

The ornamental design for a chess board, substantially as shown and described.
